UNITED STATES PATENT OFFICE.

GEORGE KOEBLER, OF WAUKESHA, WISCONSIN.

RAILWAY TIE.

Application filed May 24, 1923. Serial No. 641,184.

To all whom it may concern:

Be it known that I, GEORGE KOEBLER, a citizen of the United States, and resident of Waukesha, in the county of Waukesha 5 and State of Wisconsin, have invented certain new and useful Improvements in Railway Ties; and I do hereby declare that the following is a full, clear, and exact description thereof.

10 My invention relates to improvements in rail ties, and particularly to that type adapted for use in preventing the spreading of the rails upon a road bed.

15 The object of my invention is to provide a tie which is adapted to be used between the supporting elements of a track and to prevent the rails thereof from spreading.

20 A further object of my invention is to provide a tie constructed of several elements bolted together and the elements so formed that strain upon the bolts will be eliminated.

25 Another object of my invention is to provide a tie that can easily be removed from its engagement with the rails.

Other objects and advantages of my invention will be apparent during the course of the following description.

30 In the accompanying drawing forming a part of this application and in which like reference characters are employed to designate corresponding parts throughout the several views thereof:

35 Figure 1 is a side elevation of my improved tie showing the same positioned upon the rails of a track.

Figure 2 is a top plan view of the same, and

40 Figure 3 is a detail view of one of the lower members.

45 Referring to the drawing in detail, the numeral 1 designates a top member formed of suitable material such as iron, wood or the like, the same adapted to be positioned between the two rails of a track and between the transverse supporting elements thereof.

50 As disclosed in the drawings, the member 1 is provided with a central cut-out portion 2 and smaller L-shaped cut-out portions 3 positioned adjacent the ends of the member 1.

55 The member 1 has detachably bolted thereto on its under portion by bolts 4, the openings for which pass through the cut-outs above referred to, a pair of oppositely extending members 5 and 6, the extreme end

portion of each being provided with an upward projection 7 adapted to engage the outer side of a rail, and an undercut portion 8 to receive therein the base of the rail 9. 60 The adjacent end portions of the members 5 and 6 are each provided with a projection 10, each of which is adapted to fit within the central cut-out portion 2 and be secured thereto, by the bolts 4. The intermediate portion of 65 each member 5 and 6 is further provided with an L-shaped projection 11 which is adapted to be received within the cut-out portions 3 formed in the member 1, and bolted thereto by the bolts 12 which pass 70 through suitable openings formed in the members 5 and 6.

As disclosed in the drawing, the end portions of the member 1 are of a thickness somewhat less than the height of the rail web, thus permitting the same to fall under the ball thereof. Furthermore, it will be noted that the under portion of each end of the member 1 is cut-out, as indicated at 13 to permit the base of the rail to fit thereunder, and be supported upon the members 5 and 6. 80

In order to permit the ready placement of the member 1 between two rails, I have rounded the diagonal corners of the same as 85 indicated by the numeral 14.

To form a further brace at the central portion of the member 1, and at the point where the members 5 and 6 abut, I have placed a metallic plate 15 which is held thereto by 90 the bolts 4.

From the foregoing description it will be fully apparent that a tie of this structure can be placed upon the rails in a very little time, and in doing this the members 5 and 6 are first put in place after which the member 1 is inserted between the rails, on the inner side, and swung around so as to engage the projection carried by the members 5 and 6 and receive the same in the recesses 2 and 3 100 provided therefor, after which the three are secured together by the bolts 4 and 12. Therefore it will be noted that due to the interlocking elements carried by the members making up the tie that no strain whatsoever will fall upon the bolts, thus making the tie as one complete member.

From the foregoing, it is thought that the construction, operation and many advantages of the herein described invention will be apparent to those skilled in the art, without further description, and it will be understood 110

that various changes in the size, shape, proportion, and minor details of construction may be resorted to without departing from the spirit or sacrificing any of the advantages 5 of the invention.

Having thus fully described my invention, what I claim as new and desire to secure by Letters Patent is:—

1. A tie of the class described having a 10 main member adapted to be placed between two rails, members secured to said main member and engaging the outer side of said rails, and interlocking means carried by said main member and the second said members for 15 holding the tie in place.

2. A tie having a main member and secondary members secured thereto and adapted to receive between their opposite end portions rails, and means made integral with said 20 members for locking the tie in place.

3. A tie having a main member and second-

ary members detachably secured thereto and adapted to receive between their opposite end portions rails, and interlocking elements made integral with said members for locking 25 said tie in place.

4. A tie having a main member adapted to be placed between two rails, said member being provided with cutout portions on its under side, secondary members secured to said main member and abutting in one of said cutout portions, said secondary members adapted to hold rails at their end portions in contact with said main member, interlocking means between the main and secondary members, and means for securely fastening the 30 secondary members to said main member.

In testimony that I claim the foregoing I have hereunto set my hand at Waukesha, in the county of Waukesha and State of Wis- 40 consin.

GEORGE KOEBLER.
